DESIGN FOR A COMBINATION
KITCHEN TOOL

Samuel L. Gerson, Millville, N. J.

Application December 31, 1947, Serial No. 143,475

Term of patent 14 years

(Cl. D44—29)

To all whom it may concern:

Be it known that I, Samuel L. Gerson, a citizen of the United States, residing in Millville, Cumberland County, New Jersey, have invented a new, original, and ornamental Design for a Combination Kitchen Tool, of which the following is a specification, reference being had to the accompanying drawings forming a part thereof.

In said drawings:

Fig. 1 is a side elevational view of the combination kitchen tool, showing my new design;

Fig. 2 is a plan view of said tool; and

Fig. 3 is a transverse section of the combination kitchen tool, as viewed on the line 3—3, Fig. 1.

I claim:
The ornamental design for a combination kitchen tool as shown.

SAMUEL L. GERSON.
